(57) **CLAIM**

We claim the ornamental design for a sealed chamber for a surveillance camera, as shown and described.

DESCRIPTION

FIG. 1 is a front perspective view of a sealed chamber for a surveillance camera showing our new design;

FIG. 2 is front and side perspective view thereof, with the camera being in an alternative position and housing cover removed;

FIG. 3 is a front perspective view of a sealed chamber for a surveillance camera with the housing cover removed; and, FIG. 4 is a rear and side perspective view of a sealed chamber for a surveillance camera with the housing cover removed.

The portions of the article in broken lines are shown for illustrative purposes only and form no part of the claimed design.
